SASH VENTILATOR

Carl H. Larson, Elkhart, Ind., assignor to The Adlake Company, Elkhart, Ind., a corporation of Illinois

Application September 22, 1930, Serial No. 483,407

3 Claims. (Cl. 98—97)

The present invention has to do with sash ventilators, and is particularly concerned with an improved ventilator which, while capable of various applications, may be mounted advantageously in the top rail of a vertically slidable sash without interfering in any way with the movement of the sash.

The purpose of the invention, generally stated, is to provide an improved sash ventilator which is saliently characterized by its extreme lightness and simplicity. The improved sash ventilator is, furthermore, quite inexpensive to manufacture and install.

Other objects and advantages of the invention will be evident to those skilled in the art upon a full understanding of the novel construction of the ventilator.

In order that the invention may be readily understood, one embodiment of the same is herein illustrated and described, but it will of course be appreciated that the invention is susceptible of incorporation in other structurally modified forms coming equally within the scope of the appended claims.

25 In the accompanying drawing:

Fig. 1 is an inside face view of a top sash rail equipped with the ventilator of the invention;

Fig. 2 is an outside face view of the rail, at the location of the ventilator;

Fig. 3 is a horizontal section, taken on the line 3—3 of Fig. 1;

Fig. 4 is an irregular vertical transverse section, taken on the line 4—4 of Fig. 1; and

Fig. 5 is a fragmentary horizontal section, taken on the line 5—5 of Fig. 1.

The ventilator of the invention is adapted to be mounted in a hollow sheet metal sash rail 10, which rail is provided in its outer wall 11 with a row of apertures 12 and is provided in its inner wall 13 with a relatively large rectangular opening 14 in opposition to the row of apertures. A rectangular sheet metal frame 15 is set into the opening 14 in substantially contiguous association with the apertured portion of the outer wall 11. The frame 15 is provided with a row of apertures 16 which register with the apertures 12, and is provided with an offset marginal flange 17 which seats against a countersunk ledge 18 bordering the opening 14.

50 A rectangular wire screen 19 is positioned between the apertured portion of the outer wall 11 and the apertured portion of the frame 15. The frame 15 is held in position by means of a plurality of two-part telescoping screws 20 which

extend through aligned holes in the frame and the inner and outer walls of the rail.

The frame 15 carries a slide 21 which is shiftably attached to the inner face of the apertured portion of the frame by means of a plurality of headed studs 22, which studs project from the frame through elongated slots 23 in the slide. The slide 21 is provided with a row of apertures 24 which are adapted to move into or out of register with the apertures in the frame. The slide 21 may be shifted by means of a finger piece 25 which is attached to, and projects inwardly from, the slide intermediate the ends of the latter.

The ventilator above described can be manufactured and installed in the rail of a sash at very little expense. Since all of the parts of the ventilator are contained wholly within the contour of the rail, the ventilator will not interfere in any way with the raising of the sash, even when mounted in the top rail of the sash in proximity to a header.

I claim:

1. In a sash ventilator, the combination with a hollow sheet metal sash rail which is provided in its outer wall with a group of apertures and in its inner wall with a relatively large opening in opposition to the group of apertures, of a sheet metal frame which is set into the rail substantially flush with the opening in the inner wall in substantially contiguous association with the apertured portion of the outer wall, a screen positioned between the frame and the apertured portion of the outer wall, and a ventilating slide 25 which is carried by the frame and is provided with a group of apertures for movement into and out of register with the apertures in the outer wall of the rail.

2. In a sash ventilator, the combination with a hollow sheet metal sash rail which is provided in its outer wall with a row of apertures and in its inner wall with a relatively large rectangular opening in opposition to the row of apertures, of a rectangular sheet metal frame which is provided with a row of apertures and with an offset marginal flange providing a recessed portion and is set into the opening in the inner wall with the apertured portion of the frame in substantially contiguous registration with the apertured portion of the outer wall and with the marginal flange in lapped relation to the edge of the opening in the inner wall, a screen positioned between the frame and the apertured portion of the outer wall, and a slide which is provided with a row of apertures and is shiftably 55

mounted within the recessed portion of the frame for movement into and out of register with the apertures in the frame.

3. In a construction of the character described, in combination, a hollow sheet metal sash rail which is provided in its front wall with a horizontally elongated opening, a horizontally elongated sheet metal frame which is set back into said opening and is provided with forwardly offset marginal portions which lap with the edges

of the opening in the front wall of the rail, an adjustable ventilating device which is mounted on the set-back portion of the frame, and means for operating said ventilating device consisting of a vertically extending horizontally shiftable strip which is connected with the device and extends substantially from the top of the frame to the bottom of the same between the front and rear planes of the frame.

CARL H. LARSON. 10
